UNITED STATES PATENT OFFICE.

EMMETT MASSEY, OF PROCTOR, ARKANSAS.

SAWMILL SET-WORKS.

1,272,289.

Specification of Letters Patent.

Patented July 9, 1918.

Application filed July 10, 1917. Serial No. 179,742.

To all whom it may concern:

Be it known that I, EMMETT MASSEY, a citizen of the United States, residing at Proctor, in the county of Crittenden and 5 State of Arkansas, have invented new and useful Improvements in Sawmill Set-Works, of which the following is a specification.

This invention relates to saw mill set works for regulating the thickness of the 10 slab, board or plank cut from a log.

The invention has for its object to produce means of simple and improved construction and which may be easily operated whereby the throw of the set lever may be limited 15 and regulated.

A further object of the invention is to produce a device of the class described having a plurality of limiting stops for variously limiting the throw of the set lever, and simple and improved means whereby any one 20 of the limiting stops may be projected in the path of the lever.

A further object of the invention is to produce simple and improved means whereby, when one limiting stop is projected in 25 the path of the set lever any other limiting stop previously lying in the path of the set lever will be automatically retracted.

With these and other ends in view which 30 will readily appear as the nature of the invention is better understood, the same consists in the improved construction and novel arrangement and combination of parts which will be hereinafter fully described and particularly pointed out in the claims.

In the accompanying drawings has been 35 illustrated a simple and preferred form of the invention, it being, however, understood that no limitation is necessarily made to the precise structural details therein exhibited, 40 but that changes, alterations and modifications within the scope of the claims may be resorted to when desired.

In the drawings:

45 Fig. 1 is a view in side elevation of a saw mill set works constructed in accordance with the invention.

Fig. 2 is a side elevation as seen from the opposite side.

50 Fig. 3 is a top plan view.

Fig. 4 is a vertical sectional view taken on the line 4-4 in Fig. 1.

Fig. 5 is a vertical sectional view taken on the line 5-5 in Fig. 1.

55 Fig. 6 is a sectional view taken on the line 6-6 in Fig. 1.

Corresponding parts in the several figures of the drawings are denoted by like characters of reference.

On or adjacent to one end of the log carriage, a portion of which appears at A, is mounted a frame structure generally designated by B, said frame structure having a bearing for the set shaft C from which motion may be transmitted in any customary 60 well known manner to the head blocks (not shown,) the present invention dealing only with the means for rotating the set shaft and for varying and limiting the movement thereof. The set shaft carries a spur wheel 65 15 meshing with a pinion 16 on a countershaft 17, the latter shaft carrying also a ratchet wheel 18 of large diameter. Pivoted on the countershaft 17 are two pawl frames 19 and 20 carrying spring actuated pawls 70 21 and 22 that engage the ratchet wheel. 23 is a shaft on which is fulcrumed a lever 24, the oppositely extending arms of which are connected by links 25 and 26 with the pawl frames 19 and 20, respectively. The lever 80 24 has an upwardly extending handle 27 which will be hereinafter referred to as the set lever, said handle constituting the hand lever which is grasped and manipulated by the operator for the purpose of actuating 85 the set works. The set lever swings in the arc of a quadrant 28 which is fixed securely on the frame B, said quadrant being provided near the ends thereof with shoulders or offsets 29 and 30 whereby extreme movement of the set lever will be limited in two 90 directions. The shoulder 29 with which the lever normally contacts when at rest will be known as the front shoulder while the shoulder 30 will be known as the rear 95 shoulder.

It will be seen that when the set lever is actuated by the operator moving it back and forth, the pawls carried by the frames 19 and 20 will successively turn the ratchet 100 wheel 18 a distance governed by the throw of the set lever, the pawl actuated by one of the frames slipping idly over the ratchet teeth while the pawl carried by the other frame engages a tooth of the ratchet wheel 105 thereby turning the same. From the countershaft on which the ratchet wheel is mounted motion is transmitted by the means herein described to the set shaft, the amount of rotation of the latter being governed by 110 the throw of the set lever. For the purpose of governing and varying such throw, mech-

anism is provided which will now be described.

Fixed in the frame B are arcuate bearing members 31, 32 and 33. The frame also 5 contains an arcuate bar 34 which has been shown as being located adjacent to and slightly below the middle bearing member 32, and adjacent to the inner face of the quadrant 28. Said arcuate bar 34, for reasons which will presently appear, will be 10 known as the stop container. The bearing members 31, 32 and 33 afford bearings for a plurality of rock shafts 35 of which any desired number may be used, said rock shafts 15 being preferably arranged in substantially radial relation to the arcuate bearing members. Mounted in the frame in substantially concentric relation to the arcuate bearing members and in spaces intermediate said 20 bearing members are arcuate slides 36, the number of said slides equaling the number of rock shafts, and each slide carrying a rack 37 meshing with a pinion 38 on one of the rock shafts. Each of the rock shafts also 25 carries a pinion 39 meshing with teeth 40 formed on a slide 41 which constitutes a stop member, there being a number of such stop members equal to the number of rock shafts 35. These stop members are fitted 30 for transverse sliding movement in apertures 42 in the stop container 34 which latter, as previously stated, is substantially co-extensive with the quadrant 28 adjacent to which it is located. The said quadrant is 35 provided with apertures 43 registering with the apertures 42, and adapted to receive the ends of the stop members 41 when the latter are projected in the direction of the quadrant, thereby holding the stop members securely 40 against the impact of the set lever the movement of which in one direction the stop members 41 are designed to limit to a varied extent.

Each of the arcuate slides 36 is connected 45 at one end with a retracting spring 44. These springs serve not only to retract the slides and to maintain each slide in normal or initial position, but also, through the intermediate gearing, to maintain the stop members 41 in retracted position with respect to the quadrant 28. For the purpose 50 of actuating the slides 36 against the tension of their respective springs, to project the stop members in the path of the set lever, the following mechanism is provided.

Pivoted in the upper part of the frame B are a plurality of keys 45, each resembling an ordinary typewriter key in that it is provided with a finger piece 46, and each having an arm or lever 47. Each arm or lever 48 is connected by a link 48 with one arm 49 of a bell crank D the other arm of which, 55 is connected by a link 51 with one of the arcuate slides 36 each of which may be provided with a laterally extending arm or

bracket 52 with which one end of the link 51 may be conveniently connected. It will be seen that by depressing any one of the keys 45 one of the arcuate slides will be moved longitudinally causing the rack carried by said slide to rotate one of the rock shafts 35, thereby causing such rock shaft to project one of the stop members 41 through the medium of the pinion 39 engaging the teeth 40 of such stop member. The stop 70 container 34, as previously stated, is of arcuate form, and it is preferably concentric with the axis of the shaft 23 on which the set lever is mounted. The stop members, of which any desired number may be used, are 75 suitably spaced apart so as to variously limit the throw of the set lever, thereby 80 varying the amount of rotation of the set shaft.

In order to maintain the stop member 85 which is projected by the depression of one of the keys in a projected position, against the tension of the retracting spring 44, until it shall be desired to change the "set," there is provided a locking slide 53 of arcuate 90 form, said slide being preferably interposed between the stop container 34 and the arcuate bearing member 32. The locking slide 53 is provided in its outer side face with a plurality of sockets 54 in each of which is 95 mounted a slidable spring actuated locking member or latch 55, the number of said latches being equal to the number of rock shafts, etc. Each latch is projected outwardly from the socket in which it is mounted by a spring 56, the outward movement being limited by a stop member 57. Adjacent to each socket 54 the locking slide is provided with a concave arcuate recess 58 which is substantially concentric with one of the 100 rock shafts 35, the parts being so proportioned that each latch member or slide 55 will be projected beyond the wall of the recess 58 adjacent thereto. Each of the slides or latch members 55 is also provided with a curved notch 59 in its outer end adjacent to the side thereof which faces the recess 58, said notch, however, being spaced from the wall of the recess. Each of the rock shafts 35 carries a radially disposed locking arm 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

verse movement until the locking arm shall be released. Such releasing action may be performed automatically by the subsequent depression of another key 45 for the purpose 5 of changing the "set." By the rotation of the rock shaft actuated by the depression of such key, the locking arm of such rock shaft will presently move the locking slide against the tension of its retracting spring suffi- 10 ciently to release the locking arm of the rock shaft associated with the key that was first depressed or manipulated, thereby causing such key and the parts associated therewith to be restored to normal or initial position 15 by the action of one of the retracting springs 44.

A spring actuated releasing lever 62 is provided, said lever having an arm 63 that extends in the path of the locking slide, and 20 whereby said slide may be moved at any time in order to release any locking arm 60 that may be held thereby when, for any reason, it shall be desired to do so; for instance, when it is desired to retract all the stop 25 members 41 in order to permit the set lever to swing to the extreme limit of its movement between the stop shoulders 29 and 30.

For the purpose of protecting the mechanism of the device suitable covering mem- 30 bers 80 are provided, said covering members being preferably in the nature of slides oper- able in suitable guide members 81.

From the foregoing description, taken in connection with the drawings hereto annexed, the operation and advantages of this invention will be readily understood by those skilled in the art to which it appertains. It will be seen that the construction of the improved device is such as to permit a great 40 range of different adjustments to be made. The stop members 41 whereby the movement of the set lever in one direction is limited may be manipulated very easily by manipulation of the keys 45 which latter may previously be numbered to indicate the thickness 45 of the lumber that will be cut. Projection of any one of the stop members by means of its actuating key causes the immediate retraction, automatically, of any stop 50 member previously projected. The stop members are held very securely against the impact of the set lever not only by the stop container but also by engagement with the apertures in the quadrant 28 which will also 55 serve to guide the set lever and to limit the extreme movement thereof in both directions. The general construction is simple and inexpensive, and the improved device may be readily installed upon and used in 60 connection with log carriages having well known means of many different kinds for actuating and operating the head blocks.

Having thus described the invention, what is claimed as new is:

65 1. In a device of the class described, a set

lever, a quadrant having stop shoulders to limit the extreme throw of the lever in two directions, a stop container adjacent to and spaced from the quadrant, stop members 70 slidable in said container toward and from the quadrant, and means for actuating the stop members.

2. In a device of the class described, a set lever, a quadrant having stop shoulders to limit the extreme throw of the lever in two 75 directions, a stop container adjacent to and spaced from the quadrant, stop members slidable in said container toward and from the quadrant, and means for actuating the stop members; the quadrant being provided 80 with openings to receive the ends of the stop members when projected thereby coöperating with the stop container to hold the stop members securely against the impact of the set lever. 85

3. In a device of the class described, a set lever, a quadrant having stop members limit- 90 ing the extreme throw of the lever, a stop member consisting of a slide movable trans- versely in the direction of the quadrant to lie in the path of the set lever intermediate the stop shoulder, and means for actuating said slide including a rock shaft, pinions carried thereby, teeth on the stop member meshing with one of the pinions, an arcuate 95 spring retracted slide, and a rack carried by said slide in mesh with the other pinion on the rock shaft.

4. In a device of the class described, a set lever, a quadrant having stop members limit- 100 ing the extreme throw of the lever, a stop member consisting of a slide movable trans- versely in the direction of the quadrant to lie in the path of the set lever intermediate the stop shoulder, and means for actuating 105 said slide including a rock shaft, pinions carried thereby, teeth on the stop member meshing with one of the pinions, an arcuate spring retracted slide, a rack carried by said slide in mesh with the other pinion on the 110 rock shaft, a pivotally supported key, and connecting means between said key and the rock shaft for rocking the latter.

5. In a device of the class described, a set lever, a stop container, stops slidable in said 115 container and adapted to be projected in the path of the set lever, means for projecting the stop members, spring actuated means for retracting the stop members, means for temporarily locking and securing the stop members in projected position, and means for releasing the locking means. 120

6. In a device of the class described, a stop container, stops transversely slidable 125 therein, said stops having teeth on the faces thereof, slides movable transversely of the stop members, racks carried by said slides, rock shafts having pinions meshing with said racks and other pinions meshing with the teeth of the stop members, pivotally sup- 130

ported keys, connections between the keys and the rock shafts including bell cranks, and connecting links whereby the rock shafts may be rotated by depressing the keys, and 5 retracting springs connected with the rack carrying slides.

7. In a device of the class described, a set lever, a shaft on which the lever is fulcrumed, means for limiting the extreme 10 throw of the set lever in two directions, an arcuate stop container, stop members slideable transversely in said container and adapted to be projected in the path of the set lever, said stop members having toothed 15 faces, arcuate slides, racks carried by said slides, rock shafts supported substantially radially with respect to the shaft carrying the set lever, pinions on said rock shafts in mesh with the racks carried by the arcuate 20 slides, other pinions on the rock shafts meshing with the toothed faces of the slideable stop members, means for rotating the rock shafts, and means for retracting the arcuate 25 slides.
8. In a device of the class described, a set lever, a shaft on which the lever is fulcrumed, means for limiting the extreme throw of the set lever in two directions, an arcuate stop container, stop members slideable transversely in said container and adapted to be projected in the path of the set lever, said stop members having toothed 30 faces, arcuate slides, racks carried by said slides, rock shafts supported substantially radially with respect to the shaft carrying the set lever, pinions on said rock shafts in mesh with the racks carried by the arcuate 35 slides, rock shafts supported substantially radially with respect to the shaft carrying the set lever, pinions on said rock shafts in mesh with the racks carried by the arcuate

slides, other pinions on the rock shafts meshing with the toothed faces of the slideable stop members, means for rotating the rock 40 shafts, and means for retracting the arcuate slides, in combination with means for retaining the parts temporarily against the tension of the retracting spring.

9. In a device of the class described, a set 45 lever, a shaft on which the lever is fulcrumed, means for limiting the extreme throw of the set lever in two directions, an arcuate stop container, stop members slideable transversely in said container and adapted 50 to be projected in the path of the set lever, said stop members having toothed faces, arcuate slides, racks carried by said slides, rock shafts supported substantially radially with respect to the shaft carrying the set 55 lever, pinions on said rock shafts in mesh with the racks carried by the arcuate slides, other pinions on the rock shafts meshing with the toothed faces of the slideable stop members, means for rotating the rock shafts, and means for retracting the arcuate slides, in combination with means for retaining the parts temporarily against the tension of the 60 retracting springs, said means including radial arms fixed on the rock shafts, an arcuate spring retracted locking slide adapted to be moved by said radial arms, and spring actuated latch members carried by 65 said locking slide and adapted for engagement with the radial arms to prevent reverse rotation of the rock shafts under the influence of the retracting springs.

In testimony whereof I affix my signature.
EMMETT MASSEY.
